UNITED STATES PATENT OFFICE

160,263

ARROW NOCK

Charles M. Hunt, Fort Wayne, Ind.

Application July 26, 1948, Serial No. 147,769

Term of patent 14 years

(Cl. D34—5)

To all whom it may concern:

Be it known that I, Charles M. Hunt, a citizen of the United States, residing at Fort Wayne, in the county of Allen and State of Indiana, have invented a new, original, and ornamental Design for an Arrow Nock, of which the following is a specification, reference being had to the accompanying drawing forming part thereof, in which:

Fig. 1 is a top plan view of an arrow nock showing my new design;

Fig. 2 is a side elevational view; and

Fig. 3 is a rear end view thereof.

I claim:

The ornamental design for an arrow nock, as shown.

CHARLES M. HUNT.
